CLAIM

The ornamental design for a shelf board, as shown and described.

DESCRIPTION

1. Shelf board

1.1 : Front

1.2 : Back

1.3 : Left

1.4 : Right

1.5 : Top

1.6 : Bottom

1.7 : Perspective

1.8 : Cross sectional

1.9 : Enlarged

(Continued)

A ←

A ←

FIG. 1.8 is a cross-sectional view taken along the A-A line shown in FIG. 1.1; FIG. 1.9 is an enlarged view between B and B' shown in FIG. 1.3.
